MAINE

MANUFACTURE OF PULP ROVINGS

Application filed June 6, 1931. Serial No. 542,648.

The subject of this invention is an improvement in the manufacture of pulp rovings from comparatively short-fibered material, such as wood pulp. In the production of such rovings, it is the practice to start with an aqueous suspension of pulp and to deposit the pulp fibers progressively from the aqueous vehicle as spaced, continuous ribbons or webs on a traveling wire cloth such as used in a Fourdrinier papermaking machine. The pulp ribbons may be partially dewatered, as by suction, while still on the wire, to a moisture content at which they are most amenable to furling or rolling out into rovings or strands of substantially uniform cross-section, tensile strength, softness, etc. While it is possible to remove the damp ribbons from the wire and to direct them through the atmosphere to furling mechanism of any suitable description, nevertheless it has been found most advantageous to effect their furling and compacting while they are still supported on the wire. Thus, when furling and compacting are carried out on the form wire, there is little danger of rupturing or weakening the uniformly felted structure of the ribbons, or causing the ribbons to intermingle, even though they are damp and so tender as to be highly susceptible to spoilage.

One of the troubles which arises when the damp pulp ribbons are furled and compacted into rovings on the forming wire is that there is serious danger of skipping or of incompletely furling the ribbons, even when a friction roll, such as a wire-cloth-covered roll, is used as the instrumentality for engaging the ribbons and rolling them out into round form. We have observed that this trouble is on account of the fact that pulp fibers become entangled in the forming wire and thus cause sticking of the ribbons as a whole to the wire so as to resist engagement of the furling roll with those edges which are to serve as the starters for the furling operation. In accordance with the present invention, before the furling operation, we detach only these edge portions from the wire, so as to make positive the initiation and complete culmination of the furling operation. By detaching the edge portions on only

one side of the ribbons, the ribbons are maintained against misplacement by those fibers on their opposite edge portions still in entanglement with the wire as a result of previous forming and sucking the pulp on the wire. This feature is of utmost importance, particularly in a machine where the continuous pulp deposits or ribbons are closely spaced on the forming wire so as to realize the maximum production and where there is hence danger of causing snarls or intermingling between the ribbons during the furling operation.

With the foregoing and other features and objects in view, our invention will now be described in conjunction with the accompanying drawing, wherein

Figure 1 is a side elevation, partly in section, of a machine embodying our invention. Figure 2 constitutes a front elevation of the machine.

Figure 3 represents a sectional detail on the line 3-3 of Figure 1.

While not limited thereto, the machine chosen for illustrating our invention is of the same type as that described in application Serial No. 542,649, filed June 6, 1931, by Milton O. Schur and William B. Meglitz. That application discloses the principle of furling and compacting the pulp ribbons into rovings directly on the forming wire by means of a friction roll, preferably a roll of the same general type as the so-called dandy roll used in paper manufacture, having an effective roving surface of relatively large diameter. As shown in Figure 1, the wet or forming end of the machine may include a suction roll indicated generally by the numeral 1, and a pulp vat indicated generally by the numeral 2. A wire cloth or screen 3, such as used on a Fourdrinier machine, passes tightly about the roll 1, which is provided with spaced peripheral grooves (not shown) communicating with its interior so as to cause a deposition of pulp as spaced, continuous ribbons when an aqueous pulp suspension is run onto the roll from the vat 2. The vat is made up of a bottom 4 and side walls 5, whose front edges terminate in close proximity to the roll, so as to direct a flow of the pulp suspension onto the wire, the front edges

5a of the side walls being of an arcuate shape to conform to that portion of the roll periphery presented thereto. The roll proper is supported near its ends in suitable bearing members 6, and is rotated by suitable means (not shown), thereby serving to drive the wire in the direction indicated by arrow. The vat, only the front or delivery portion of which is shown, continuously receives a supply of pulp suspension of suitable consistency from a supply pipe (not shown). The suspension is delivered under a baffle plate or false bottom 7, which acts to confine the flow frontwardly. The pulp suspension flows onto the wire, and the aqueous vehicle passes through the wire into the roll only over those areas or zones immediately in back of the spaced peripheral grooves, as a result of which ribbons of pulp are deposited on the wire. In order that a uniformly textured or interfelted deposit of pulp be made, an excess of highly dilute pulp suspension is delivered into the vat, the excess taking the course indicated past the clearance or throat space 8 between the baffle and the roll, and thence over the baffle to the rear of the vat, where it is removed and returned to the source of supply. The pulp suspension employed may be of a consistency of only about 1/40%, or even less, in which case large quantities of water are removed during the formation of the pulp ribbons. To this end, a suction chamber 9, occupying a sector somewhat greater than the periphery portion of the roll in contact with the pulp suspension, may be arranged inside of the roll, so as to accelerate withdrawal of the water from the pulp suspension and thus to promote the formation of pulp ribbons on the wire. The wire carrying the pulp ribbons out of the pulp suspension may then pass over a smaller second suction chamber 10 adjacent to the chamber 9. In depositing on the wire, the pulp fibers assume a preponderantly longitudinal lay, particularly when the wire is traveling at such speeds as 500 feet per minute, or greater. A certain amount of cross-laying and random-laying of the fibers inevitably ensues, particularly on account of the turbulence and eddying of the pulp suspension as it flows through the clearance 12 and the currents of water cascading into the roll.

The wire carrying deposits of pulp ribbons proceeds horizontally from the roll 1 over the desired number of suction boxes 11 maintained under sufficient suction to dewater the ribbons to a water content of about 250% to 300%, more or less, based on the weight of fiber. At this water content, the ribbons are amenable to ready furling into rovings or round bodies; and, in accordance with our invention, the furling action is made positive, uniform, and complete. To this end, the wire passes over a pressure box 12, whereinto a gaseous medium under pressure, such as com-

pressed air, is delivered by a pipe 13 from a pump or pressure chamber (not shown). The compressed air is emitted from the box, as best shown in Figure 3, through a series of apertures 14 arranged transversely of the top 15 of the box with which the wire makes tight frictional contact. The apertures register with or subtend the edge portions on only one side of the ribbons, each air blast having the effect of progressively lifting the edge portion of a ribbon from the wire as the wire moves thereover, without, however, weakening, rupturing, or dislodging the ribbons from their initial placement. In fact, the lifting is only temporary and merely detaches the edge portions of the ribbons from the wire, so that the initiation of the subsequent furling or convoluting action thereupon is rendered easy and positive. The wire then passes over a guide roll 16, whence it takes a vertically downward course to a spaced guide roll 17. The vertical wirestretch 18 between the rolls 16 and 17 is where the furling can be most conveniently accomplished. For this purpose, a furling dandy roll 19, whose periphery is covered with wire cloth of, say, 40 or finer mesh, is shown in engagement with the confronting stretch 18 over an appreciable arc of contact, the axis of the roll being inclined at an angle of, say, 80°, more or less, to the direction of travel of the wire and the ribbons supported thereon. The wire-cloth covering may be fixed, as by welding, to a series of spaced rings 20, constituting the rims of spiders 21 and anchored to the shaft 22 for the roll. The roll shaft may be journaled for rotation in a pair of brackets 23 extending from a transverse bar 24 toward the wire 18. As the pulp ribbons, indicated by the numeral 25 in Figure 2, enter the nip of the wire 18 and the roll 19, the relative angular movement between the wire and the roll causes a furling or lateral rolling out of the ribbons into round form, with the edge portions previously detached from the wire affording an easy furling start, particularly as the damp ribbons are pliable and of a quasi-dough-like consistency. The furling roll may be positively driven, although, as illustrated, the rotation of the roll is attained by frictional contact with the traveling wire. The furling or roving action conditions the pulp ribbons into uniform, round bodies or strands 26, detached or readily detachable from the wire as they issue from the nip. The strands may be collected continuously as by a pneumatic system, such as described and claimed in application Serial No. 504,029, filed December 22, 1930, by Milton O. Schur. After collection, the rovings may be twisted, plied into yarns or strings, and dried. Provision is preferably made to vary the angle of inclination of the furling roll 19, for which purpose the bar 24 may have a centrally located pivot pin 27, normally fixed at

its outer or threaded end by a nut 28 to the cross-member 29 of a pair of spaced standards 30. If desired, bolts 31, positioned near the ends of the bar 24, may project through 5 arcuate slots 32 in the cross-member 29, so as to permit firm fixture of the roll to the cross-member by nuts 33. In adjusting the angularity of the roll, the three nuts are loosened, and, after the roll has been swivelled to the 10 desired angularity, the nuts are tightened down against the member 29. In returning to the suction roll 1 from the roll 17, the wire takes an inclined upward course over the tightening roll 34 and then runs substantially 15 horizontally over a guide roll 35 to the suction roll.

The combination of instrumentalities described is subject to modification, particularly as regards the means for forming or 20 depositing the pulp ribbons from aqueous suspension on the wire and the mechanism for furling the ribbons, although the assembly of the vat, suction roll, forming wire, and furling roll has been found to give excellent 25 results in actual practice. We do not, however, claim these various features per se or in combination, except in so far as they enter into our invention. Our invention, as already indicated, devolves about the detachment 30 of the edge portions on only one side of the ribbons deposited on the forming wire, so that furling or roving of the ribbons directly on the wire may be positively and uniformly effected to completion with little, 35 if any, liability of damaging or destroying the uniformity of texture or formation realized at the wet end of the machine, and with little, if any, danger of snarling or intermingling the ribbons during furling or roving, 40 even when they are as closely spaced as $\frac{1}{2}$ to $\frac{3}{4}$ inches apart. By positive and uniform furling action, we mean that there is a greatly reduced tendency for the roll to miss or skip 45 engaging the detached edge portions of the ribbons, and, as a result, there is secured the desired convolution of the ribbons into round bodies or strands entirely free from raggedness or lines of cleavage in their structure.

What we claim is:

- 50 1. A method which comprises progressively depositing from aqueous suspension pulp fibers as ribbons on a traveling wire cloth, progressively detaching the edge portions of the ribbons on only one side from the wire, and frictionally engaging the detached edge portions and rolling out the ribbons into round form while still on the wire. 55
2. A method which comprises progressively depositing from aqueous suspension 60 pulp fibers as ribbons on a traveling wire cloth, only partially dewatering said ribbons on the wire, progressively detaching the edge portions of the ribbons on only one side from the wire, and frictionally engaging the detached edge portions and rolling out the 65

damp ribbons into round form at an angle to the direction of travel of the wire.

3. The combination with a traveling wire cloth and means for progressively depositing from aqueous suspension spaced ribbons 70 of pulp on said cloth, of means for detaching the edge portions of the ribbons on only one side from the cloth and means for engaging the detached edge portions and furling the ribbons into round form while on the wire. 75

4. The combination with a traveling wire cloth and means for progressively depositing from aqueous suspension spaced ribbons of pulp on said cloth, of means for delivering blasts of gaseous medium under the edge portions of the ribbons on only one side to lift said edge portions from the cloth and a roll frictionally engaging said cloth and ribbons and arranged at an angle of inclination to the direction of travel of said cloth so as to engage the lifted edge portions and roll the ribbons into round form. 80

5. The combination with a traveling wire cloth, means for progressively depositing from aqueous suspension spaced ribbons of 90 pulp on said cloth, and means for partially dewatering said ribbons on said cloth, of means for delivering blasts of gaseous medium under the edge portions of the ribbons on only one side to lift said edge portions from the cloth and a roll whose periphery is covered with wire cloth frictionally engaging said traveling cloth and ribbons and arranged at an angle of inclination to the direction of travel of said cloth so as to engage the lifted edge portions and roll the ribbons into round form. 95

In testimony whereof we have affixed our signatures.
